UNITED STATES PATENT OFFICE

130,814

DESIGN FOR A MOTORCYCLE HANDLE BAR GRIP

Charles A. Comiskey, Chicago, and Gordon A.
Willey, Elmhurst, Ill.

Application September 29, 1941, Serial No. 103,554

Term of patent 7 years

To all whom it may concern:

Be it known that we, Charles A. Comiskey, a citizen of the United States and resident of Chicago, in the county of Cook and State of Illinois, and Gordon A. Willey, a citizen of the United States and resident of Elmhurst, in the county of Du Page and State of Illinois, have invented a new, original, and ornamental Design for a Motorcycle Handle Bar Grip, of which the following is a specification, reference being had to the accompanying drawing, forming part thereof.

Fig. 1 is a perspective view of a motorcycle handle bar grip showing my new design; and
Fig. 2 is a side elevational view thereof.

We claim:

The ornamental design for a motorcycle handle bar grip, as shown.

CHARLES A. COMISKEY.
GORDON A. WILLEY.
